FILE HOLDER

Merl Alden Jaynes, Visalia, Calif.

Application May 3, 1944, Serial No. 533,882

3 Claims. (Cl. 29—80)

This invention appertains to new and useful improvements in file holders designed to facilitate the work of filing saws or other objects that require an exact angle or degree of slant, such as the teeth of cross-cut saws, rip saws, etc.

An important object of the invention is to provide a handle and chuck combination for holding files wherein the chuck can be rotated to permit setting of the file with its filing surface in the correct angle with respect to the work, thus making it unnecessary that a person slant or tilt his hand to an awkward position to get the correct angle.

Other objects and advantages of the invention will become apparent to the reader of the following description.

In the drawings:

Figure 1 represents a side elevational view of the tool.

Figure 2 is an end elevational view with the file removed.

Figure 3 is a top plan view of the holder.

Figure 4 is a fragmentary sectional view of the holder.

Figure 5 is a front elevational view of the clamp box.

Figure 6 is an end elevational view with the clamp box removed.

Figure 7 is a perspective view of the cam.

Referring to the drawings wherein like numerals designate like parts, it can be seen that the holder consists of a pistol-grip 5 having an upward forward face 6. The grip 5 has a recess 7 extending inwardly from the face 6 and this serves to receive a socket 8, this socket 8 being anchored in place by a screw or the like 9. The outer end of the socket 8 has a riser 10 formed with a threaded opening for receiving one end of a threaded member 11 on which a clamp disk 12 is feedable. A finger-grip pin 13 projects from the clamp disk 12.

A lock nut or jamb nut 14 is provided on the threaded member 11 and engages the riser 10 as shown in Figure 4. It is preferable that the jamb nut 14 has a slight taper so that it will have a portion on the same plane as the outermost surface of a collar 15 formed on the intermediate portion of an elongated barrel 16, to the end that when the locking disk 12 is screwed inwardly on the threaded member 11 to engage the collar 15 to hold the barrel 16 in the correct rotated position, the disk 12 will also engage the nut 14 and thus adding more frictional retention to the holding ability of the lock disk 12.

A substantially square-shaped clamp box 17 is 55

provided on the outer end of the barrel 16, the barrel 16 having a reduced portion 18 thickened as at 19 and over this portion the clamp box 17 is disposed. The thickened portion 19 has a file tang receiving V-shaped groove 20 and as is shown in Figure 5, the inside bottom portion of said box 17 has a V-shaped groove 21 also for engaging the tang of a file.

The upper forward portion of the frame 17 has a notch 22 therein for receiving an upstanding pin 23 on the portion 19 of the barrel 16.

A wing head-equipped set screw 24 is feedable down through the upper portion of the frame 17 to engage the portion 19 of the barrel 16 in order that the lower portion of said box 17 is clamped firmly in place, gripping a file tang between the grooved portion 21 of said box 17 and the grooved portion 18 of the barrel 16.

Obviously, whenever desired, the lock disk 12 can be unloosened and the barrel 16 rotated to bring the desired indicating point 25 on the periphery of the collar 15 opposed to a pointer 26 on the upper portion of the hand-grip 5.

Crossed degree lines 27, 28 may be provided on the top of the hand-grip 5 to indicate the angle at which the file should be held while at an angle of 60 degrees which is the usual angle for filing cross-cut saws.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A holder for files comprising a hand grip having a forwardly opening recess therein, a socket secured in said recess with an open front end, a barrel extending forwardly out of said socket and rotatable therein into different angular positions, means coacting with the forward end of said barrel to clamp a file therein, and means to frictionally lock said barrel in different angular positions comprising a riser on said socket extending above the hand grip, a circumferential collar on said barrel adapted to be clamped against said front end of said socket, a threaded member extending forwardly of the riser, and a locking disc on said member adapted to be turned against said collar to clamp the same between the disc and said front end of the socket, said disc having a radial finger grip pin thereon.
2. A holder for files comprising a hand grip

having a forwardly opening recess therein, a socket secured in said recess with an open front end, a barrel extending forwardly out of said socket and rotatable therein into different angular positions, means coacting with the forward end of said barrel to clamp a file therein, and means to frictionally lock said barrel in different angular positions comprising a riser on said socket extending above the hand grip, a circumferential collar on said barrel adapted to be clamped against said front end of said socket, a threaded member extending forwardly of the riser, and a locking disc on said member adapted to be turned against said collar to clamp the same between the disc and said front end of the socket, said disc having a radial finger grip pin thereon, and a jam nut on said member intermediate the disc and riser for turning against said disc.

3. A holder for files comprising a hand grip having a forwardly opening recess therein, a socket secured in said recess with an open front

end, a barrel extending forwardly out of said socket and rotatable therein into different angular positions, means coacting with the forward end of said barrel to clamp a file therein, and means to frictionally lock said barrel in different angular positions comprising a riser on said socket extending above the hand grip, a circumferential collar on said barrel adapted to be clamped against said front end of said socket, a threaded member extending forwardly of the riser, and a locking disc on said member adapted to be turned against said collar to clamp the same between the disc and said front end of the socket, said disc having a radial finger grip pin thereon, said coacting means comprising a reduced portion on the barrel and a clamping element through which said portion extends and provided with a clamping screw bearing against said portion for adjusting the element into clamping relation to said portion.

MERL ALDEN JAYNES.
